CLAIM

The ornamental design for a control device, as shown and described.

DESCRIPTION

FIG. 1 is a front perspective view of a control device according to the present invention.

FIG. 2 is a front view of the control device of FIG. 1.

FIG. 3 is a rear view of the control device of FIG. 1.

FIG. 4 is a left side view of the control device of FIG. 1.

FIG. 5 is a right side view of the control device of FIG. 1.

FIG. 6 is a top view of the control device of FIG. 1; and,

FIG. 7 is a bottom view of the control device of FIG. 1.

The broken lines immediately adjacent to the claim depict the bounds of the claimed design, while all other broken lines are directed to environment. In addition, the unshaded surfaces that directly adjoin both solid and broken lines form no part of the claimed design. The broken lines form no part of the claimed design.
